EDWIN W. PARKER, OF ROCHESTER, NEW YORK.

PHOTOGRAPHIC-SHUTTER CASING.

No. 826,269.

Specification of Letters Patent.

Patented July 17, 1906.

Application filed December 27, 1904. Serial No. 238,305.

To all whom it may concern:

Be it known that I, EDWIN W. PARKER, of Rochester, in the county of Monroe and State of New York, have invented certain new and 5 useful Improvements in Photographic-Shutter Casings, of which the following is a specification.

The present invention relates to casings for photographic shutters, and has for its object to provide a device of this character which shall be stronger, more durable, more easily assembled, and less expensive to manufacture than are those devices of this character now in use.

At the present time shutter-casings usually consist of short cylindrical metal boxes having two principal parts, one of which is a flat plate having a cylindrical flange or rim and the other a plate adapted to be secured to the flange, these parts having provisions for holding the lens of the camera and the mechanism of the shutter. Such casings are difficult and expensive to manufacture, as it is hard to form such a long flange as is necessary upon one of the casing members, and also the barrels or cylinders of the pumps by which the shutter mechanism is operated are attached to the casing by means of brackets, which sometimes are not sufficiently secure and at any time are liable to become loose and give trouble.

By my invention I have constructed a casing consisting, essentially, of two plates, each of which is provided with a cylindrical flange, and when the parts are assembled to make the complete casing the flanges meet and a cylindrical box results which is divided on a line substantially midway of its longitudinal extent. Also a novel means for securing the pump-barrels to the casing is provided.

Of the accompanying drawings, Figure 1 represents an elevation of a shutter-casing constructed according to my invention. Fig. 45 2 represents a plan view of the shutter-casing as seen from above. Figs. 3 and 4 represent sectional views on a somewhat enlarged scale, taken on lines 3 3 and 4 4, respectively. Fig. 5 represents a fragmentary elevation of 50 a portion of one of the casing members, showing the inside of the casing with one of the pump-cylinders in section in the position it occupies relatively to the casing when the

parts are assembled. Fig. 6 represents a perspective view of one of the pump-cylinders. 55

The same reference characters indicate the same parts in all the figures.

a and *b* are the two main members of which the casing is made, and each of these members consists of a substantially flat plate 60 *a'* *b'* and a peripheral flange *a²* *b²*, which is preferably cylindrical, although not necessarily so. The flanges may be made separately and secured to the plates in any approved manner, or they may be formed integral with the plates, which is the preferred construction. The two flanges are of equal diameter, and in assembling the parts of the casing are placed with their projecting edges in contact and are held together by means of 70 bolts *c*, extending through one of the plates and threaded into the other. Preferably the flanges *a²* and *b²* are of the same height, so that neither will need to be of excessive extent, and the labor and difficulty of drawing 75 the flanges will be reduced to the minimum. One of the flanges, as *a²*, is provided with an extension or lip *d*, of slightly-larger diameter, projecting from the outer edge and extending over the flange *b²* of the other member of the 80 casing. This lip constitutes a guide for retaining the members in proper relation while they are being assembled.

The pump barrels or cylinders are designated by *e* *e*, one of them being the cylinder 85 to which the bulb is connected and having a piston for operating the shutter mechanism, while the other contains the retarding-piston, by which an exposure of an appreciable length of time is secured.

In ordinary constructions the pump-barrels are secured to the casing by brackets brazed or otherwise connected thereto; but by my invention I have provided an improved method of attachment which is simpler to make and is more durable, while at the same time the ease with which the pump-barrels may be secured to the casing is greatly increased. On opposite sides of the casing in the cylindrical portions of the casing members are formed recesses *f* of a shape such as to receive a portion of a pump-barrel placed alongside the casing with its axis extending in a direction at right angles to the axis of the casing. The greatest width of 105 the recesses is practically the same as the di-

ameter of the pump-barrel to be placed therein, so that when the pump-barrels are assembled with the casing members approximately half of the width of the barrels will 5 extend into the casing. It is not essential that the pump-barrel should extend exactly to this amount into the casing; but the construction which permits this is preferred, as thereby the greatest firmness is secured.

10 Each pump-barrel is gripped between the flanges of the casing members and is retained securely by means of a plate g of approximately elliptical shape securely fastened to the exterior of the pump-barrel and curved 15 to conform to the curvature thereof, its exact outline being the same as that of the periphery of the recess in which the pump-barrel is placed. In assembling the parts the pump-barrel is placed with the plate g extending 20 into the interior of the casing, with its edges engaging against the flanges of the casing members around the periphery of the recess upon the inside. The flanges a^2 b^2 are brought together outside of the plate g , and 25 the casing members are secured together by the bolts c . Thus as the plate g contained within the casing is greater in lateral extent than the area of the recess in which the pump-barrel is held it is obvious that the latter can- 30 not be removed as long as the casing members are bolted together unless the plate g is pulled off or the flanges broken, and that also the joint or narrow opening between the barrel and the casing is covered by the edges of 35 the plate, whereby light and dust are effectually prevented from passing through such joint into the interior of the casing. The casing members are provided with the usual apertures h i for admitting light and provi- 40 sions j for mounting a lens. The portion of each pump-cylinder projecting into the casing is formed with a slot k , through which the portion of the shutter mechanism to be engaged by the pump-piston is permitted to ex- 45 tend.

I claim—

1. A photographic-shutter casing comprising a pair of plates having oppositely-extended flanges meeting at their edges, means for 50 holding said plates together, and pump-cylinders held between portions of said flanges.

2. A casing for a photographic shutter divided on a line approximately midway of its longitudinal extent into two members, each 55 of said members comprising in part a rim or flange extended toward the other member and in engagement with the flange of the other member when said members are assembled, said flanges having recesses for receiving a portion of a pump-cylinder.

3. A casing for a photographic shutter divided on a line approximately midway of its longitudinal extent into two members, each

of said members comprising in part a rim or flange extended toward the other member 65 and in engagement with the flange of the other member when said members are assembled, and means for retaining said flanges in alignment, said flanges having recesses for receiving a portion of a pump-cylinder.

4. A casing for a photographic shutter divided on a line substantially midway of its longitudinal extent into two members, each of said members comprising in part a rim or flange extended toward the other member 70 and in engagement with the flange of the other member when said members are assembled, and an external annular bead connected to the flange of one of said members adjacent its edge arranged to engage and surround a portion of the flange of the other member.

5. A photographic-shutter casing consisting of a plurality of members, a pump-barrel, and a projection mounted on said barrel extending between adjacent portions of the 85 casing members and gripped thereby.

6. A photographic-shutter casing having an aperture in its side, a pump-barrel, and means extending into the aperture for connecting the pump-barrel with a portion thereof, said connecting means being arranged to exclude dust and light from said aperture.

7. A photographic-shutter casing having an aperture in its side, a pump-barrel, and 95 means extending into the aperture for connecting the pump-barrel with a portion thereof comprising a projection mounted on the pump-barrel and arranged to engage the edges of the aperture on the inside of the cas- 100 ing.

8. A photographic-shutter casing consisting of members having oppositely-extending engaging flanges constituting the sides of the casing, said sides being recessed to form an 105 aperture, a pump-barrel, and a plate mounted on the barrel arranged to engage the edges of the aperture on the inside of the casing and to be gripped and held in place by the casing members when they are assembled.

9. A photographic-shutter casing consisting of members having oppositely-extending engaging flanges constituting the sides of the casing, said sides being recessed to form an 115 aperture, a pump-barrel, a plate mounted on the barrel arranged to engage the edges of the aperture on the inside of the casing and to be gripped and held in place by the casing members when they are assembled, and means for holding the flanges of said members in alignment.

10. A photographic-shutter casing consisting of members having oppositely-extending engaging flanges constituting the sides of the casing, said sides being recessed to form an 125 aperture, a pump-barrel, a plate mounted on

the barrel arranged to engage the edges of the aperture on the inside of the casing and to be gripped and held in place by the casing members when they are assembled, means for holding the flanges of said members in alignment, and means for holding the members together.

In testimony whereof I have affixed my signature in presence of two witnesses.

EDWIN W. PARKER.
